BOTTLE CRATE

Alphonso Taurman, Birmingham, Ala.

Application September 25, 1944, Serial No. 555,633

5 Claims. (Cl. 220—21)

1

This invention relates to a bottle crate, particularly of the type employed in handling carbonated beverages and the like, and has for an object the provision of a crate of the character designated which shall be of relatively light weight, comparable to the weight of wooden crates heretofore employed, and which shall have the requisite strength to withstand rough handling.

A further object of my invention is to provide a bottle crate of the character described which shall be formed of sheet metal, formed to shape and welded together, and which shall present no exposed rough or sharp edges endangering the hand of a person handling the crate.

A further object of my invention is to provide a metal bottle crate of the requisite weight and strength, and which shall be so formed as to provide drains for liquid when held in any position, thereby affording a means for galvanizing the crate after it is assembled.

Other important objects of my invention are to provide a metal bottle crate embodying flanged sleeves for holding the bottles in place in the crate and which are so disposed as to provide important reinforcing means for the sides and top of the crate; also, a bottle crate formed from sheet metal with holes punched in the top to receive the flanged sleeves and so formed as to provide stiffening flanges around the opening; and further, to provide a metal bottle crate, formed from sheet metal, which shall have depressed sides and corner longitudinal channels providing stiffening and a depressed panel for lettering.

In accordance with my invention, I employ a light weight sheet steel blank folded to form a rectangular tube with reinforcing channels along the corners. Flanged sleeves extend downwardly through the top to hold the bottles in place, which sleeves are welded into the top and at the sides of the crate thereby providing substantial reinforcement. The sides and ends of the crate are so shaped as to provide the maximum of strength with a minimum of weight, and the bottom of the crate is provided with stiffening flanges formed from the material of the bottom, and so arranged as to provide drains which permit the escape of any liquid from the crate which would otherwise corrode the metal. This design also permits galvanizing of the crate after it is assembled.

The foregoing and other important features of my invention are illustrated in the accompanying drawings forming a part of this application, in which

2

Fig. 1 is a top plan view partly in section, of a crate made in accordance with my invention;

Fig. 2 is a bottom plan view of the same;

Fig. 3 is an end elevational view of the crate;

Fig. 4 is a longitudinal sectional view along the lines IV—IV of Fig. 1;

Fig. 5 is a transverse sectional view taken along the lines V—V of Fig. 4;

Fig. 6 is a fragmentary end view of a top corner 10 of the crate, drawn to a larger scale;

Fig. 7 is a detail elevational view of one of the ends and showing fragments of the bottom of the crate;

Fig. 8 is a fragmentary plan view of the parts 15 shown in Fig. 7;

Fig. 9 is an elevational view of the center partition;

Fig. 10 is an enlarged detail sectional view taken along lines X—X of Fig. 6; and

Fig. 11 is a detail sectional view showing the joining of the sleeves to the top of the crate.

Referring now to the drawings for a better understanding of my invention, my improved bottle crate embodies a body portion 10 formed from 25 a single sheet of metal into a tube generally rectangular in shape with the edges of the sheet of metal meeting in part in the bottom as shown at 11 in Figs. 5 and 8, and welded together. As the sheet of metal is folded over to form the 30 rectangular tube, I form longitudinal corner channels 12, 13, 14 and 16 which protrude outwardly, overhanging the sides, forming depressed side panels 17 and 18 between them, to which lettering may be applied and thus be protected from 35 damage. The channels 12, 13, 14 and 16 also provide stiffening and additional strength for the corners of the crate. In the bottom of the body portion I form longitudinally extending corrugations or channels 19 and 21 which provide additional stiffening for the bottom. The ends of 40 the channels 19 and 21, as may be seen in Figs. 4 and 8 are stopped short of the ends of the crate and are left open to provide drainage. Also, for the major portion of the length of the body portion I cut out and turn up edges 22 and 23 of 45 the sheet forming the tube as described, which edges form stiffening flanges running substantially the length of the crate, as may be seen in Figs. 4, 5 and 8. The flanges are stopped short of the ends of the crate and the openings in the bottom thus formed provide drainage for any liquid which might otherwise be trapped in the 50 bottom of the crate.

In bending the sheet to form the body portion, 55 I also bend back the end edges as shown at 24

and 26 to form open channels which extend substantially all around the end of the body portion, but which are necessarily closed at the corners as shown at 27 in Fig. 6.

The ends of the crate are each formed from a piece of sheet metal 28 with the edges turned outward to form top and bottom flanges 29 and 31 and end flanges 32 and 33, with the corners cut out as shown in Figs. 6, 7 and 8. The edges of the corners are bent backwardly as indicated by the dotted lines 34 in Fig. 7 so that no sharp edge is presented. The flanges 29, 31, 32 and 33, are hooked into the open end flanges of the body portion 24 and 26 as shown in Fig. 4 and the ends spot welded along said channels to the sheet, as shown at 25 in Fig. 10, forming the body portion. There is thus formed a smooth, or rounded edge substantially all around the ends of the crate with three thicknesses of metal and with inturned flanges on the body portion and outturned flanges on the ends. The cutout portions at the corners of the end provide additional drainage for any liquid which might otherwise be trapped in the crate.

Extending across the center of the crate is a reinforcing partition 36 (see Figs. 4 and 9). The partition 36 is formed from sheet metal with its ends and edges turned back to form stiffening flanges 37 and 38 across the top and bottom of the partition, respectively, and 39 and 41 at the ends of the partition. The corners are cut away as shown at 42 to provide for drainage around the ends of the partition. Also, as may be seen in Fig. 8, the bottom of the partition is notched out at 43, 44 and 46 to clear the stiffening corrugations 19 and 21 and the upturned flanges 22 and 23. The upper edge of the partition 36 is also notched out as shown at 47, 48, 49 and 51 to form drains when the crate is inverted. In order to provide clean out holes, the ends and the partition may be cut out as indicated at 55 and 60 in Figs. 7 and 9, turning the edges of the end openings over as indicated by dotted lines.

The top of the body portion 10 is punched out as shown in Figs. 1, 4 and 5 to provide rows of longitudinally and transversely extending openings 52 for the reception of bottles. In forming the openings 52 the edges therearound are turned down as shown at 53 to provide reinforcing flanges. In the openings 52 are inserted sheet metal sleeves 54 formed with flanges 56 which overhang the top of the body portion and are joined thereto by welding as indicated at 65 in Fig. 11. Also, as shown in Figs. 4 and 5, the outer rows of sleeves extend downwardly into the crate abutting the sides and ends of the crate and are joined to the sides and ends by welding, as indicated at 70 in Fig. 10, thereby forming a major reinforcement for the crate. It will be seen that by providing the sleeves 54 and welding their flanges to the top, and by welding the body portions of the outer rows to the sides of the crate, I am enabled to employ a very light gauge sheet metal for constructing the crate and the sleeves and at the same time provide the maximum of stiffness and strength, so as to withstand the rough handling to which such crates are subjected.

At the ends of the crate I provide handles each formed from a piece of sheet metal with the bottom rolled over to form a tube 57 and with the body portions 58 turned inwardly at 59 to form a flange which is welded to the top, overhanging the end of the crate. The ends of the body portion 58 are turned inwardly, as shown at 61, in

Fig. 1, and joined to the end of the crate. I thus provide a handle which may be readily grasped without danger of injury to the person handling the crate.

From the foregoing it will be apparent that I have devised a beverage bottle crate made of sheet metal which is light of weight, rugged of construction, and which can withstand a maximum of rough handling.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. A bottle crate comprising a body portion formed from a single sheet of metal bent in the shape of a rectangular tube with the edges meeting in part and welded together at the bottom and in the other part bent upwardly to form stiffening flanges and drainage openings in the bottom, said body portion also having the ends bent backward to form open channels along the edges, ends for the crate made of sheet metal having the edges turned outward and fitted into and joined to the said channels, downwardly flanged openings for bottles formed in longitudinal and transverse rows in the top, and outwardly flanged sleeves fitting into the openings with their flanges overhanging the top and joined thereto.

2. A bottle crate comprising a body portion formed from a single sheet of metal bent in the shape of a rectangular tube with the edges meeting in part and welded together at the bottom and in the other part bent upwardly to form stiffening flanges and drainage openings in the bottom, said body portion also having the ends bent backward to form open channels along the edges, ends for the crate made of sheet metal having the edges turned outward and fitted into and joined to the said channels, downwardly flanged openings for bottles formed in longitudinal and transverse rows in the top, and outwardly flanged sleeves fitting into the openings with their flanges overhanging the top and joined thereto, and means joining the outer rows of sleeves at their sides to the sides and ends of the crate.

3. A crate as defined in claim 2 in which the corners of the ends are cut way to afford drainage.

4. A relatively light sheet metal bottle crate comprising a body portion formed from a single sheet of metal bent in the form of a rectangular tube with reinforcing channels along the corners forming depressed side panels, the edges of said sheet meeting in part in the bottom of the body portion and being turned up in part to form stiffening flanges and a drain opening in the bottom, the end edges of said body portion being turned inwards to form open channels, a partition formed of sheet metal with edges turned over and joined to the body portion midway the ends thereof, ends formed of sheet metal with edges turned and entered into the channels formed by the inwardly turned edges of the body portion, said ends being cut away at the corners to provide drains, and a plurality of longitudinally and transversely extending rows of reinforced openings for bottles formed in the top of the body portion.

5. A relatively light sheet metal bottle crate comprising a body portion formed from a single sheet of metal bent in the form of a rectangular

tube with reinforcing channels along the corners forming depressed side panels, the edges of said sheet meeting in part in the bottom of the body portion and being turned up in part to form stiffening flanges and a drain opening in the bottom, the end edges of said body portion being turned inwards to form open channels, a partition formed of sheet metal with edges turned over and joined to the body portion midway the ends thereof, ends formed of sheet metal with edges turned and entered into the channels formed by the inwardly turned edges of the body portion, said ends being cut away at the corners to provide drains, and a plurality of longitudinally and transversely extending rows of sleeves for bottles extending downwardly through the top and joined thereto by welding, and the outer of said rows also being joined to the ends and sides of said crate by welding.
